MULTIPLE STAGE CEMENTING

Roland E. O'Donnell, Odessa, Tex., assignor to
Halliburton Oil Well Cementing Company,
Duncan, Okla.

Application November 27, 1936, Serial No. 112,950

5 Claims. (Cl. 166—1)

This invention relates to the cementing of oil wells or the like, and more particularly to an arrangement for cementing long strings of casing or pipe in stages so that all of the cement which fills the annular space surrounding the casing may be supplied thereto without passing around the bottom of the casing.

The multiple stage cementing of wells is now well known to those skilled in the art. The method and apparatus for accomplishing this is fully disclosed in the United States patent to Halliburton, No. 1,860,669, granted May 31, 1932, and in the reissue thereof, No. 19,570, reissued May 14, 1935.

15 In the multi-stage cementing of wells a valve structure, usually called a multi-stage unit, is made up with the casing. The arrangement is such that at the proper time the valve in this unit is opened so that cement can flow outwardly therethrough to the annular space surrounding the casing. The valve may be a sleeve valve, as taught in the patents mentioned above, and may be opened by one of the cementing plugs used in the multiple stage cementing operation.

25 As taught in the above mentioned patents, a multiple stage cementing operation usually employs several plugs. Thus, for example, in the illustration in Figs. 9 and 10 of the reissued Patent No. 19,570 two plugs travel through the multi-stage unit without affecting the same, a third plug enters the multi-stage unit and opens the valve and a fourth plug follows the slug of cement which flows through the multi-stage unit.

30 It sometimes happens in such a multi-stage cementing operation as that described that the plugs which are intended to pass through the multi-stage unit without opening the valve do not do so but become wedged therein and open the valve prematurely.

40 It is one object of the present invention to devise means insuring the proper operation of a multi-stage cementing apparatus to overcome the difficulty just mentioned.

45 It is a further object of the invention to provide means for scraping and cleaning a portion of a casing mounted beneath a multiple stage unit to prevent cement from clinging thereto and interfering with subsequent operations in the well. In this connection it is to be noted that in a multiple stage system, as described in the aforementioned patents, where the second plug placed in the well must pass through the multiple stage unit it must be of small diameter and of a flexible nature so as to pass through the multiple stage unit. It is incapable, therefore, of scraping the walls of the casing beneath the multiple stage unit to the desired extent.

50 Other objects and advantages reside in certain novel features of the construction and operation of the parts, as will be apparent from the

following description taken in connection with the accompanying drawing, in which:

Fig. 1 is a vertical cross-sectional view of the casing of an oil well with a multiple stage unit mounted therein and showing two of the plugs used in the cementing operation thereof;

Fig. 2 is a view similar to that of Fig. 1 but showing a second operation of the unit and showing a third plug approaching the multiple stage unit; and

Fig. 3 is a view similar to that of Fig. 1 but showing the position of the plugs at a still later operation of the unit.

Referring to the drawing in detail, and first to the arrangement illustrated in Fig. 1, a casing of an oil well is there shown as having an upper section 11, a multiple stage unit 12, an intermediate section 13 below the multiple stage unit and a lower section 14 to which a floating collar or guide shoe 15 is attached.

20 The multiple stage unit 12 includes a valve arrangement, port or openings 16 being provided in the main body of the unit, which ports are normally closed by means of an inner sleeve 17 held in position by means of shear pins 18. The 25 interior of the sleeve 17 is provided at its lower end with a conical flange or seat 17a for purposes which will presently be described.

The parts of the multiple stage unit just described are old and well known to those skilled in the art. The novelty in the present arrangement involves the supporting of a female plug 19 on the upper end of the section 13 of the casing but below the multiple stage unit. To accomplish this the plug 19 has an aluminum or other 30 metallic or hard ring 20 attached thereto at its upper end. This ring 20 has a flange 21 which rests upon the upper end of the section 13 of the casing and holds the plug 19 in place. As shown in Fig. 1, the plug 19 has a central aperture or 35 opening 22 through which cement or other fluid may pass. In addition the plug 19 has the usual fabric or rubber flexible cups 23 and 24 which aid in maintaining a seal between the plug and the casing.

40 The plug 19 is mounted in the casing as it is made up and is placed on the upper end of the section 13 just before the multiple stage unit 12 is secured thereto.

In cementing a well with this equipment the 50 slug of cement which is to pass around the bottom of the casing is first pumped into the well and this first slug of cement which is to pass around the bottom of the casing is followed by a male plug 25. Mud or other fluid is then pumped 55 into the well and forces the cement downwardly through the female plug 19 and around the bottom of the casing.

The plug 25 is substantially solid in nature and has a depending portion 26 and the usual 60

flexible cups 27 and 28. The plug 25 passes readily through the multiple stage units, the cup members 27 and 28 being sufficiently flexible to readily pass through the sleeve 17 without catching 5 on the flange 17a. As the pumping is continued the plug 25 seats within the plug 19 and the two pass together downwardly through the lower portion of the casing.

Following the first slug of cement plug 25 and 10 the separating body of mud or the like, a third plug 29 enters the casing beneath the second slug of cement. This plug is shown just above the multiple stage unit in Fig. 2 and seated on the flange 17a in Fig. 3. To cooperate with the flange 15 17a the plug 29 is provided with a seating member 30 of frusto-conical shape. As this plug seats upon the flange 17a it moves the sleeve 17 downwardly opening the ports 16 so that the second 20 slug of cement may flow outwardly through the ports 16. The second slug of cement is followed by a fourth plug, designated 31, in accordance with usual practice.

In normal operation the plugs 19 and 25 remain in the relative position shown in Fig. 2 after 25 they have once united and pass downwardly through the casing together. Before the plug 19 can pass downwardly the flange 21 must shear off as shown in Fig. 3 and as the plugs 19 and 25 pass downwardly the ring 20 scrapes the wall of 30 the casing and scours it of all cement which might later harden and interfere with the continued operations in the well. In order for the flange 21 to shear, the plug 25 must tightly seat against the plug 19 and the pressure created by 35 the pump used in forcing the cement into the well is sufficient to shear the ring 21.

To insure the proper seating of the plug 29 in the sleeve 17, it is desirable to provide means for separating the plugs 19 and 25 should they reach 40 the bottom of the well before the plug 29 reaches its seat on the sleeve 17. To accomplish this the collar or shoe 15 is provided with a centrally disposed stud 32 adapted to contact with the extension 26 on the plug 25 and remove it from 45 its socket in the plug 19, thus allowing cement to flow through the passage 22 in the plug 19. The stud 32 has longitudinal passageways connecting with radial slots, so that fluid may flow 50 downwardly through the shoe 15 even through the plug 19 is seated thereon. As stated above, this action takes place only when the plugs 19 and 25 arrive at the bottom of the well before the plug 29 is seated. In normal operation the plugs 19 and 25 are not separated.

55 In the arrangement illustrated, no No. 1 plug is used. That is, there is no plug beneath the first slug of cement which enters the well. If it is desired to employ a No. 1 plug it will be apparent to those skilled in the art that a female plug corresponding to that shown at 19 may be mounted beneath the plug 19 and a small male plug adapted to pass through the plug 19 may be placed in the well beneath the first slug of cement to engage the lower female plug and pass 60 downwardly therewith. It has been found, however, in normal multi-stage cementing operations that it is unnecessary to have a plug pass downwardly beneath the first slug of cement and the arrangement shown in the drawing is sufficient 65 to carry out a complete multi-stage cementing operation.

It will be apparent to those skilled in the art that, although but one embodiment of the invention has been shown and described herein, various changes may be made in the arrangement and construction of parts without departing 5 from the spirit of the invention or the scope of the annexed claims.

I claim:

1. The combination with a casing of an oil well and a multiple stage cementing unit incorporated therein of a male plug and a female plug, said female plug being mounted in the casing beneath the multiple stage cementing unit and held in position by shearable means, the arrangement being such that the male plug may be pumped down the well behind a slug of cement and contact the female plug to cause the shearing of said shearable means whereupon the female plug may pass downwardly within the casing to scrape the walls of the same.

2. Apparatus for use in the multiple stage cementing of the casing of a well comprising a number of plugs and a multiple stage cementing unit consisting of a structure made up with the casing and having a valve and means adapted 25 to open the valve when one of said plugs contacts the multiple stage unit, one of said plugs having means for detachably mounting the same on the casing beneath the multiple stage unit and another of said plugs being adapted to pass 30 through said multiple stage cementing unit without opening said valve and to actuate said mounting means to cause the disconnecting of said detachably mounted plug from the casing to cause the detachably mounted plug to pass down- 35 wardly and scrape the wall of the casing.

3. Apparatus for use in the multiple stage cementing of wells, including a casing, having a multiple stage cementing unit, made up with the casing, a plug detachably mounted on the casing 40 beneath said multiple stage unit and means for detaching said plug, after a slug of cement has passed therethrough, to cause the same to pass downwardly and scrape the casing beneath said multiple stage unit.

4. Apparatus adapted for use in oil wells and comprising a casing, valve means mounted therein, a female plug detachably mounted in the casing beneath said valve means, a male plug for 45 contacting the female plug to aid in detaching the same from the casing and to cause the same to pass downwardly within the casing and a plug for causing the valve means to open and permit the passage of fluid from the interior of said casing to the exterior thereof without passing 50 around the bottom of the casing.

5. Apparatus adapted for use in oil wells and comprising a casing, valve means mounted therein, a female plug detachably mounted in the casing beneath said valve means, a male plug for 55 contacting the female plug to aid in detaching the same from the casing and to cause the same to pass downwardly within the casing, a plug for causing the valve means to open and permit the passage of fluid from the interior of said casing to the exterior thereof without passing around the bottom of the casing and means at the bottom of the casing for separating said male and female plugs.
